UNITED STATES PATENT OFFICE.

JAMES W. BRUNDEGE, OF MONTGOMERY CITY, MISSOURI.

DESIGN FOR A KITCHEN-CABINET.

SPECIFICATION forming part of Design No. 28,667, dated May 17, 1898.

Application filed March 4, 1898. Serial No. 672,605. Term of patent 3½ years.

To all whom it may concern:

Be it known that I, JAMES W. BRUNDEGE, a citizen of the United States, residing at Montgomery City, in the county of Montgomery and State of Missouri, have invented and produced a new and original Design for Kitchen-Cabinets; and I do hereby declare the following to be a full, clear, and exact description of the same, reference being had to the accompanying drawing, forming a part thereof.

The figure is a perspective view.

The essential feature of my invention resides in the unitary design for a kitchen-cabinet, as herein described, and shown in the drawing.

The cabinet consists of bins 1, having sloping lids 2, doors 3, an inclined table or board

4, front doors 6, and cupola bins 7, 8, and 9. The bin 8 projects above the top plane of the bins 7 and 9, and the front of the bins have 20 ornamentalations 10, which are connected or joined by ornamental pieces 11, presenting a continuous ornamental front to the said three bins.

Having thus described my invention, what 25 I claim is—

The design for a kitchen-cabinet as herein shown and described.

In witness whereof I hereunto set my hand in the presence of two witnesses.

JAMES W. BRUNDEGE.

Witnesses:

J. R. APPLING,
J. O. BASKETT.
